UNITED STATES PATENT OFFICE.

EBENEZER A. W. JEFFERIES, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

GAS-PRODUCER.

1,240,220.

Specification of Letters Patent. Patented Sept. 18. 1917.

Application filed January 2, 1913. Serial No. 739,635.

To all whom it may concern:

Be it known that I, EBENEZER A. W. JEFFERIES, a citizen of the United States, residing at Worcester, in the county of Worcester and Commonwealth of Massachusetts, have invented a new and useful Improvement in Gas-Producers, of which the following is a specification, accompanied by drawings forming a part of the same.

- 10 My present invention relates to certain improvements in gas producers for the production of fuel gas from coal, and it relates more particularly to means for the feeding and disposition of fuel in the gas producing chamber whereby, among other objects, greater efficiency of operation and uniformity of product is secured as hereinafter described, the novel features being pointed out in the annexed claims.
- 20 In the accompanying drawings I have illustrated my present invention by its embodiment in practical forms of construction which may, however, be modified in various particulars without departing from my invention as described in the accompanying claims.

In the drawings,

Figure 1 represents a vertical sectional view of the upper portion of the heating chamber of a gas producer, showing a fuel feeding mechanism embodying my invention.

Fig. 2 is a central sectional view of the fuel magazine shown upon a plane at right angles to that shown at Fig. 1, and

Fig. 3 is a vertical sectional view of the upper portion of the gas producing chamber, showing a modified form of the fuel feeding mechanism.

- 40 Similar reference characters refer to similar parts in the different figures.
- Referring to Fig. 1, 1, 1 denote the upper portion of the vertical walls of a gas producer inclosing a gas producing chamber 2. It will be understood that the portions of the gas producer shown in the accompanying drawings form part of a gas producing apparatus having means for the admission of air at the bottom of the gas producing chamber for the support of combustion and with means for the removal of ashes, all of which may be of any known and suitable form of construction, but not herein shown or described as they will be familiar to those conversant with this class of mechanisms.

The walls 1, 1 inclosing the gas producing chamber 2 are designed to contain the mass of fuel 3 to which a rotating movement is imparted by the rotation of the wall 1 by any suitable actuating mechanism, in the present instance consisting of an annular rack 4 attached to the wall 1 and engaged by a gear 5 upon a rotating shaft 6. The gas producing chamber 2 is provided with a stationary cover 7 having a passage 8 for the delivery of gas and having water sealed connections 9, 9 with the rotating wall 1 of the producer.

Suspended within an opening 10 in the stationary cover 7 is a fuel magazine 11 having a cover 12 at its upper end, upon which is mounted a fuel hopper 13 communicating with the magazine 11 through a central opening which is provided with a rotatable, damper 14, or other suitable means, by which the central opening may be opened and closed at will in the operation of feeding fuel from the hopper 13 to the magazine 11. The cover 12 is provided with an annular depending flange 15 entering an annular water sealing chamber 16 supported by the cover 7. The magazine 11 is suspended by links 17 from a cable 18 which passes over rollers 19, 19 and is wound several times about a drum 20, the end of the cable being attached to a counterbalance 21.

Carried by the shaft of the drum 20 is a ratchet wheel 22 engaged by a retaining pawl 23. A hand wheel 24 is provided for the shaft of the drum 20, enabling the latter to be rotated by the attendant for the purpose of raising and lowering the fuel magazine 11. The fuel magazine 11 is held from rotating by means of a lug 25 projecting from the outer wall of the water sealing chamber 16 and entering a groove 26 formed upon the outside of the depending annular flange 15. The magazine 11 may be of any desired form in cross section, in the present instance it is represented as rectangular and is disposed eccentrically to the gas producing chamber 2. The lower edge or inner side of the magazine 11 abuts, or is in close juxtaposition to the side wall 1 of the gas producing chamber 2, while the lower edge of the opposite side is substantially in the center of the gas producing chamber, as represented in sectional view in Fig. 1.

A rotative movement is given to the wall 1 and mass of fuel 3, moving the latter in

the direction of the arrows 27, 27 Fig. 2, and the side of the magazine 11 toward which the mass of fuel is moved is double and incloses a water chamber 28, in which 5 a water circulation is maintained by means of pipes 29 and 30 connected with a water circulatory system.

The side of the magazine 11 inclosing the water chamber 28 has its outer wall 31 extending vertically downward to the level of the fuel 3 in the gas producing chamber. The water chamber is provided with an oblique bottom 32 extending downward into the mass of fuel 3, and the lower portion 33 10 of the inner wall extends obliquely upward forming a contracted opening 34 at the bottom of the magazine between a vertical wall 35 and the rounded tip or toe 36 of the water chamber 28. A water chamber 37 extends 15 around the lower edge of the magazine and communicates with the water chamber 28, thereby preventing the burning away of the lower edge of the magazine by the heating of the incandescent fuel in the gas producing chamber. The tip, or toe, 36 of the water chamber 28 extends slightly below the vertical walls 31 and 35, thereby producing a leveling or compression of the fuel as the latter is moved beneath the oblique bottom 20 32 and allowing a sheet of fuel from the magazine 11 through the contracted opening 34 to be distributed evenly over the mass of incandescent fuel, forming a uniform layer of fresh fuel extending from the center of 25 the gas producing chamber to the outer wall 1 and covering the mass of incandescent fuel at each complete revolution of the latter.

As the fuel is consumed in the gas producing chamber, an accumulation of ashes 30 forms beneath the fuel bed which tends to impede the flow of air therethrough according to the depth of the accumulated ashes, thereby checking the combustion of fuel in the gas producing chamber. The variation 35 in the supply of air can be controlled by the removal of ashes. The removal of ashes, however, tends to lower the surface of the incandescent fuel 3. In case the fuel magazine were to be held in a fixed vertical position, the lowering of the fuel bed would 40 cause an increased flow of fuel from the magazine until the mass of fuel 3 was brought substantially to the level of the lower end of the magazine, thereby causing 45 an increase in the thickness of the fuel mass corresponding to the decrease in the thickness of the stratum of ashes. Even with the uniform deposit of ashes beneath the fuel bed, it is sometimes desirable to increase or 50 decrease the thickness of the fuel bed according to the quality of fuel employed, some classes of fuel producing the best results with a comparatively thick fuel bed while others require a thin fuel bed for the most 55 efficient operation of the producer. I am 60

able to raise or lower the surface of the fuel bed within the gas producing chamber and, consequently, to regulate the thickness of the fuel bed by the vertical adjustment of the magazine 11. If the removal of ashes 70 lowers the fuel bed 3 and it is undesirable to increase the depth of the fuel, the retaining pawl 23 is removed by means of the hand wheel 24 and the fuel magazine is lowered to bring the top of the fuel 3 at the desired 75 level. If, on the other hand, an increase in the depth of the fuel bed is desirable, the fuel magazine is raised by the rotation of the drum 20 to bring the top of the fuel bed to the desired level. The conditions required for the most efficient operation of the producer relating to the level of the fuel in the gas producing chamber, or to the thickness of the fuel bed, are, therefore, under 80 the control of the operator. 85

In Fig. 3 I have shown a modification in which the upper part 38 of the fuel magazine is held in a vertical position, being rigidly attached to the cover 7 of the gas producing chamber. The lower portion 39 of the fuel magazine is inclosed by a vertically adjustable wall 40 which is made double to inclose a water chamber 41 suspended from the lower ends of water pipes 42 connected with a water circulatory system. 90 The wall 43 inclosing the upper portion 38 of the fuel magazine is likewise water cooled and the lower wall 40 has a telescopic or sliding connection over the outside of the upper wall 43. The pipes 42, 42, are connected by a cross bar 44 suspended from a cable 45 which passes over the rollers 19 and is wound several times about the drum 20 and is provided with the counterbalance 21. Attached to the pipes 42 are the inverted cups 46 which dip in the water reservoir 47 formed on the cover 7. 95 100 105

Certain subject-matter shown and described herein, is claimed in my copending application Serial No. 782,561, filed August 2, 1913. 110

I claim:

1. A gas producer comprising a section inclosing a chamber for the reception of fuel, a fuel magazine eccentric to said section and with its lower end arranged to rest upon the fuel in said chamber, and means for causing relative rotation between said section of the producer and said magazine to cause the lower end of the magazine to 115 move along the surface of the fuel, the edge of the delivery opening at the lower end of the magazine being lower at its side nearest the approaching fuel than at its opposite side. 120

2. A gas producer comprising a section including a chamber for the reception of fuel, a fuel magazine, and means for causing relative rotation between said section of the producer and said magazine, the maga- 125 130

zine having an inclined bottom wall arranged to contact with the surface of the fuel within said section of the producer, there being a fuel delivery opening in the lower end of said magazine at the side of said wall opposite the approaching fuel.

3. A gas producer comprising a section inclosing a chamber for the reception of fuel, a fuel magazine entering said chamber eccentrically thereto and provided with a scraping lower end arranged to rest upon the fuel in said chamber, means for producing a relatively rotative movement between said magazine and the surface of the fuel in the said chamber, and means for vertically adjusting said magazine relatively to said section to vary the level of fuel therein.

4. A gas producer, comprising a gas pro-

ducing chamber, a vertically movable fuel magazine therein, and means for imparting 20 a rotative movement to the surface of the fuel in said gas producing chamber relative to said fuel magazine.

5. A gas producer, comprising a fuel section, means for varying the level of fuel in 25 said section, comprising an adjustable supply magazine having its contents directly superimposed on the fuel contained in said section, and means for rotating said section relatively to said magazine.

Dated this twenty-sixth day of December, 1912.

EBENEZER A. W. JEFFERIES.
